APPARATUS FOR SEALING CONTAINERS

William D. Bell, Columbus, Ohio, assignor to
Anchor Hocking Glass Corporation, Lancaster,
Ohio, a corporation of Delaware

Application April 8, 1939, Serial No. 266,913

18 Claims.

(Cl. 226—82)

My invention relates to apparatus for sealing containers. It has to do, more particularly, with apparatus for applying closures to containers, such as food containers and including jars, bottles, cans, et cetera, and sealing them on the containers and for producing a partial vacuum in the upper ends of the containers.

One of the objects of my invention is to provide a greatly simplified apparatus for applying and sealing closures on containers and for creating an effective vacuum in the space at the upper end of the container between the closure and the contents of the container which will aid in preventing spoilage of the contents and will also aid in keeping the closure in position on the container.

Another object of my invention is to provide apparatus of the type indicated which is of such a nature that the closure and upper end of the container and the head space between the contents and the closure will be sterilized during the sealing operation.

Another object of my invention is to provide apparatus of the type indicated which will vacuumize and seal the container quickly and effectively.

Another object of my invention is to provide a machine of the type indicated which is of a very simple structure and, therefore, can be built at a relatively low cost, which will occupy a small amount of space, and which is composed of a minimum number of parts tending to wear or become inoperative.

Another object of my invention is to provide a machine of the type indicated which may be readily adjusted to operate upon containers of various sizes.

Another object of my invention is to provide a machine of the type indicated which will automatically adjust itself to containers varying in height to a limited degree.

Another object of my invention is to provide a machine which will be continuous in operation and which will perform its operations during movement of the containers and without handling of the containers by an operator.

In its preferred form my invention contemplates the provision of apparatus for applying closures to and sealing them on various containers such as jars, bottles, cans et cetera. According to my invention, the filled containers are placed indiscriminately on a continuous moving conveyor. During the movement of the containers by the conveyor, caps or other closures are loosely positioned on the upper ends of the con-

tainers. The containers are then moved to devices which will center them on the conveyor and also space them uniformly along the conveyor. They are then moved to a sealing head. This sealing head will operate on the containers during their progressive movement. It is provided with means which will automatically lift the cap from the upper end of each container, withdraw air from the head space at the upper end of each container, inject steam into such space, and then force the cap into permanent engagement with the upper end of the container, all of these operations being performed substantially simultaneously and during the progressive movement of the container. After the cap is sealed on the container, the steam previously injected into the head space of the container will condense, creating an effective vacuum within the container which will aid in holding the cap in position and will also aid in preventing spoilage of the contents of the container.

Various other objects and advantages will be apparent from the following description.

The preferred embodiment of my invention is illustrated in the accompanying drawings wherein similar characters of reference designate corresponding parts and wherein:

Figure 1 is a view partly in side elevation and partly in vertical section illustrating a machine constructed in accordance with my invention.

Figure 2 is a plan view of the machine shown in Figure 1.

Figure 3 is an enlarged perspective view, partly broken away, showing the cap-feeding and applying means and the sealing head unit.

Figure 4 is a vertical section taken through the sealing head unit and operating means associated therewith.

Figure 5 is a transverse section taken substantially along line 5—5 of Figure 4.

Figure 12 is a plan view of the structure shown in Figure 11.

Figure 13 is a side elevation of a slightly modified form of cap-feeding means.

Figure 14 is a vertical section illustrating a hydraulically operated sealing head unit.

Figure 15 is a perspective view illustrating my machine with the hydraulic sealing head unit applied thereto, the cap-feeding means not being shown.

With reference to the drawings, I have illustrated a machine which I preferably use in performing my invention and which comprises generally a table 1 supporting a conveyor unit 2 on its upper end, a cap-feeding and applying unit 3 and a sealing head unit 4. All of these units will be described in detail hereinafter.

The table 1 may be of cast iron or steel plates and comprises supporting legs 5 and an upper housing portion 6. The top of the housing is formed by the top plate 7 of the table. The bottom of the housing is formed by a removable plate 8. As will be explained later, the housing 6 is adapted to contain most of the driving mechanism of the machine. At each end of the housing adjacent the top of the table a pair of outwardly projecting supporting beam members 9 are provided. These beam members have their inner ends integrally secured together. These beam members are adapted to support the conveyor unit 2.

The conveyor unit 2 comprises a belt 10 (Figure 2) which is composed of a series of steel slats hinged together in a suitable manner to form a continuous flexible belt. The belt 10 is secured in a suitable manner at its side edges to endless sprocket chains 11. These chains pass around a pair of driving sprockets 12 keyed on a transversely extending shaft 13 supported in bearings provided in the outer ends of one of the pairs of supporting beams 9. These chains also pass around idler sprockets 14 keyed to a transversely extending shaft 15 supported in bearings on the outer ends of the other pair of supporting beams 9. Thus, a continuous flexible conveyor belt is provided which is positively driven by the sprocket and chain drives. The belt 10 is of a width just sufficient to bridge the space between the supporting beams 9. The upper flight of the conveyor passes through a channel 16 (Figure 3) formed in the top of the table 1. The conveyor slats slide over the top plate 7 of the table. The lower flight of the conveyor passes through slots 17 formed in the ends of the housing portion 6 of the table. Within this housing adjacent each slot 17 is an idler roller 18 which prevents the conveyor from contacting with the lower edge of the slot.

The conveyor is continuously driven by means of a longitudinally extending shaft 19 (Figure 2) which is rotatably supported in a bearing 20 secured to the outer end of one of the beams 9 and in a bearing 21 secured within the housing 6. This shaft 19 has keyed on its outer end a bevel gear 22. This bevel gear 22 meshes with a bevel gear 23 keyed on the outer end of transverse shaft 13 which carries the conveyor driving sprockets 12. The inner end of the shaft 19 (Figure 8) has a gear 24 keyed thereon which meshes with a gear 25 keyed on one end of a short shaft 26 which is rotatably mounted in bearing members 27 secured to one wall of the housing 6. The opposite end of the shaft 26

has a bevel gear 28 keyed thereon which meshes with a bevel gear 29 (Figure 9) keyed on a vertically disposed shaft 30 which is rotatably mounted in suitable bearings secured to the housing. This shaft also has a bevel gear 31 keyed on its lower end which meshes with a bevel gear 32 keyed on one end of a horizontally disposed shaft 33 which is rotatably mounted in suitable bearings secured to the housing. One end of this shaft 33 projects into a speed-reduction gear unit 34. This gear unit 34 is driven by an electric motor 35 through the medium of a chain and sprocket drive 36. Thus, it will be apparent that the electric motor 35 serves to continuously move the conveyor.

As indicated in Figure 1, the containers are placed indiscriminately on the conveyor and are moved in the direction of the arrow by the conveyor. My invention is not limited to any particular type of container and cooperating cap, but for illustrative purposes I have shown a container which has at its upper end a reduced portion 37 adapted to receive a cap 38. This cap preferably embodies a substantially disk-like portion 39 (Figure 6) which has a depending annular skirt 40 which carries an annular gasket 41 therewithin. When the cap is forced down onto the reduced portion 37, the frictional contact of the gasket with the reduced portion of the container will aid in maintaining the cap in position and will seal the cap on the container.

After the containers are positioned on the conveyor they are first carried between a pair of fingers 42. These fingers 42 extend over the conveyor as illustrated best in Figure 3. The ends of fingers 42 are adapted to be spaced apart just sufficiently to permit a container to pass therebetween. Furthermore, the fingers 42 are so disposed that as the articles move along on the conveyor they will strike these converging fingers 42 and will be positioned exactly at the center of the conveyor. The rear end of the fingers 42 are carried by sleeves 43 which are pivotally mounted on vertical pins 44 secured to beams 9. These sleeves 44 have radially projecting loops 45 formed thereon on which block members 46 are pivotally mounted. These block members 46 are provided with threaded openings with which threaded portions 47 of a transversely extending shaft 48 cooperate. The shaft 48 is mounted on the beams 9 in such a manner that it is free to rotate but will not move longitudinally. It may be rotated by a knurled wheel 49 keyed on one end thereof. It will be apparent that when this wheel 49 is rotated the ends of the fingers 42 will be moved equal distances towards or away from each other. Thus, the spacing of these fingers may be adjusted easily and quickly in accordance with the size of the containers to be sealed. Thus, the fingers 42 will serve to center the containers on the conveyor belt.

The containers are then carried by the conveyor to the cap-feeding and applying unit 3. This unit is illustrated best in Figures 1 to 3 and 11 to 13. The cap feeding and applying unit comprises a downwardly inclined and curved runway or chute 50. This chute 50 is composed of a pair of spaced angle members 51. These angle members 51 are inclined downwardly and their lower ends are curved to such an extent that the lower portions thereof are substantially horizontal and almost parallel with the conveyor. The caps are adapted to rest on the members 51, the members

51 being spaced properly so that the caps will bridge such space. The members 51 may be adjusted towards and away from each other so that the chute is adaptable to caps of varying diameters. For this purpose the members 51 are carried by blocks 52 having threaded openings formed therein through which a shaft 53 passes that has oppositely threaded portions cooperating with the blocks. This shaft 53 is rotatably carried in bearings secured to bracket members 54. The shaft 53 may be rotated by a knurled knob 55 keyed on the end thereof. The shaft is so mounted in the bearings that it will not move longitudinally. Thus, when the shaft 53 is rotated by means of the knob 55, the members 51 will be moved towards and away from each other so that the chute can be adjusted to fit caps of any size.

It will be apparent that the caps will lie flat on the members 51 and will slide down the chute in edge-to-edge relationship. In order to prevent one cap from riding up on the adjacent cap, I provide a member 56 which is spaced slightly above the members 51 and extends parallel thereto. This member 56 has a flat lower surface which will be almost in contact normally with the top surfaces of the caps and which will prevent them from riding up onto each other. This member 56 is rigidly carried by a bar 57 which has its ends secured to brackets 58. These brackets 58 have collars 59 which are disposed on the upper ends of vertical posts 60. The collars 59 may be adjusted up or down on the posts 60 and held in adjusted position by tightening setscrews 61. This will vary the distance between members 56 and members 51. Thus, the chute may be adjusted for caps of different thickness as well as for caps of different diameters. The brackets 54 which carry the shaft 53 are also provided with collars 62 disposed on the posts 60 and which may be held in adjusted position thereon by means of setscrews 63. Thus, the members 51 may also be raised or lowered as a unit.

As indicated in Figure 12, each of the members 51 is provided at its lower end with a finger 64 pivoted at 65 to a bracket 66 attached to the side of members 51. The outer end of each of these fingers 64 is provided with an inwardly directed portion 67 adapted to engage the edge of the lowermost cap as it leaves the chute. A spring 67a is associated with the pivot point 65 and tends to force the fingers 64 inwardly into engagement with the cap. It will be apparent from Figure 12 that the member 56 terminates a short distance upwardly from the lower ends of the members 51. This member 56 carries at its lower end a finger 68 (Figure 11) which is pivoted to a lug formed on the top thereof as at 69. The finger 68 extends beyond the lower end of member 56 and has a depending portion 70 disposed a short distance above the extreme lower ends of members 51. A stop member 71 in the form of a setscrew is provided on the finger and engages the member 56 to limit downward movement of the lower end of the finger. A spring 72 has its lower end connected to the rear end of the finger 68 and its upper end connected to a bracket 73 which is also secured to the member 56. This spring tends to throw the lower end of the finger 68 downwardly and, as stated before, this movement is limited by the stop 71. As indicated in Figure 11, this stop 71 is normally so adjusted that the portion 70 of the finger will almost contact with the rear portion of the cap as it leaves the chute. However, it will not contact

with the cap unless the rear portion of the cap tends to tilt upwardly.

The lower end of the cap-chute also has a flexible rubber roller 74 associated therewith. This roller is positively driven and will bear upon the top of the lowermost cap as the cap is withdrawn from the cap chute and will aid in the withdrawal of the cap from the chute. This roller is keyed on a transversely extending shaft 75. The outer ends of this shaft are rotatably mounted in bearing members 76. These bearing members 76 are carried on the forward ends of arms 77. These arms 77 are carried adjacent their rear ends by outwardly projecting pivot pins 78 which are secured to the members 51. The rear ends of these members 77 are joined together (Figure 3) by a bar 79 which extends transversely thereof. In order to determine the vertical position of the roller 74, a pair of stop members 80 in the form of setscrews are provided on the members 51. The lower ends of these screws bear against the bar 79. It will be apparent that if these screws are screwed downwardly, it will cause the roller 74 to be raised and vice versa.

In the operation of this cap-feeding and applying unit, the caps will be fed into the upper end of the chute either manually one by one or automatically from a magazine. They will slide down through the chute by gravity until the lowermost cap assumes a position in which it projects beyond the end of the chute, as illustrated in Figure 11. The lowermost cap will be held from falling out of the runway by the spring-pressed fingers 64 which will contact with the periphery thereof at opposite points slightly in advance of the diameter thereof. The roller 74 will not yet contact with the top of the cap and the portion 70 of finger 68 will also normally not be in contact therewith. It will be noted that the skirt of the cap is thus disposed in a position where it will be contacted by the mouth of the jar or container as it is moved along by the conveyor below the cap chute. The cap feeder as a whole is adjustable to accommodate jars of different height. The soft rubber roller 74 is driven in a manner to be explained later from the driving mechanism of the conveyor belt. It is driven at a rate of speed which is such that the rate of travel of this roller substantially approximates the rate of travel of the conveyor belt. This roller is driven in a clockwise direction (Figure 11) and it serves to bear upon the top of the lowermost cap as this cap is withdrawn from the cap feeder by the jar passing beneath the lower end of the chute and engaging the skirt of the cap. This engagement of the roller with the cap helps withdraw the cap and any tendency of the jar to be upset by the resistance to the withdrawal of the cap from the cap feeder is thereby overcome.

In order to drive the roller 74, as indicated, the shaft has a sprocket 81 keyed on one end thereof. A sprocket chain 82 passes around this sprocket. This sprocket chain also passes around a sprocket 83 keyed on one end of a transverse shaft 84 rotatably carried by the brackets 54. The opposite end of the shaft 84 carries a sprocket 85 which is keyed thereto and which is driven by a sprocket chain 86. The sprocket chain 86 is driven from the conveyor-driving means in a manner to be described subsequently.

It will be apparent that the posts 60 which support the cap-feeding chute are carried at the rear ends of supporting arms 87. These arms 87 extend forwardly parallel with the conveyor and are secured at 88 to a plate 89 which is disposed

in parallel relationship to the conveyor and above the conveyor. The manner in which this plate 89 is supported will be described later.

It will be apparent that the cap-feeding and applying means will apply the caps to the upper ends of the containers in such a manner that they will merely rest loosely thereon. It will also be apparent that as the containers pass to the cap-applying means, the fingers 42 properly center them relative to the cap-applying means. Furthermore, it will be apparent that when the containers leave the cap-applying means, they are still indiscriminately spaced on the conveyor. Therefore, before the containers reach the sealing head unit 4 it is desirable that they be spaced uniformly at predetermined distances on the conveyor.

For accomplishing this I provide the structure illustrated best in Figures 3 and 9. This structure comprises a pair of fingers 90 which extend inwardly towards the center of the conveyor belt and towards each other and which also extend in a direction opposite to the direction of movement of the conveyor belt. The inner ends of these fingers are normally moved towards each other sufficiently to prevent a container from passing therebetween. However, at regular intervals the fingers are spread apart to permit passage of a container. The fingers 90 are keyed to the upper ends of vertically disposed shafts 91 rotatably mounted at each side of the conveyor belt on the top of the table 1. Each of these shafts 91 has a lever 92 keyed to its lower end. One of the levers 92 is pivoted at 93 to one end of a rod 94. The other lever 92 is pivoted at 95 to a link 96 which is also pivotally connected to the rod 94 as at 97. The opposite end of the rod 94 is pivoted at 98 to the end of a plunger 99 mounted for reciprocation in a sleeve 100 which is secured to the inner surface of the top plate of the table. A spring 101 is associated with this plunger 99 and is of the compression type normally tending to keep the plunger in its outermost position. The plunger at its outer end carries a roller or cam follower 102 which bears against the edge of a cam 103 keyed to the vertical shaft 30 previously referred to. As previously explained, the shaft 30 is driven by the same means which drives the conveyor. Thus, the cam 103 will be rotated in timed relationship with the movement of the conveyor. The cam member 103 is provided with a cam portion 104 adapted to contact at regular intervals with the follower 102. This will force the plunger 99 inwardly moving the rod 94 longitudinally in the direction of the arrow (Figure 9) and causing the fingers 90 to swing away from each other thereby allowing the containers to pass.

It will be apparent that as the containers are moved away from the cap-applying unit, each of them will come in contact with the fingers 90. The conveyor will continue to move but the container will remain stationary, merely sliding relative to the surface of the belt. However, after the container is prevented from moving with the conveyor for a predetermined length of time to properly space successive containers on the conveyor, the fingers 90 will be spread apart permitting the container to continue its movement along with the conveyor. The cam portion 104 is so shaped that the fingers will quickly return to their original position to prevent passage of two containers simultaneously.

In Figure 10, I have illustrated slightly different means for accomplishing this. In this in-

stance, at each side of the conveyor I provide vertical shafts 91a which have keyed on their upper ends arms 90a. These arms are curved inwardly from the pivot points 91a but the major portion of each arm is normally parallel with the path of movement of the conveyor. The arms 90a are spaced above the conveyor belt and are disposed at the center thereof. The two arms 90a form a channel between which the containers carried by the conveyor will pass. Each arm is provided with a series of inwardly directed lugs 90b of progressively increasing size. The arms 90a are swung away from each other at regular intervals by means of a lever 94a which has one end rigidly secured to a rotatable disk 94b and the other end connected by a pin-and-slot connection 94c to one of the arms 90a. A lever 94d is also rigidly secured to the disk 94b and has a roller 102a on its outer end engaging a cam 103a. It will be apparent that when the cam 103a rotates the lever 94d will be swung as indicated in Figure 10. A spring 101a maintains the roller in engagement with the cam. Swinging of the lever 94d also causes the lever 94a to swing which swings the arm 90a, to which it is connected, outwardly. In order to simultaneously swing the other arm 90a outwardly to the same extent, each of the shafts has an inwardly extending lever 92a keyed to the lower end thereof and which have their inner ends connected together by pin-and-slot connections 93a. These levers 92a are disposed below the conveyor belt. It will be apparent that movement of the arm 90a connected to lever 94a is also transmitted to the other arm 90a.

In the operation of this device, the containers will be moved between the arms 90a. Each container will strike at least one pair of the lugs 90b. If it happens that the first pair of lugs are spaced apart and the container misses these lugs, it will be engaged by the succeeding pair of lugs. The successive lugs 90b project inwardly increasing distances to compensate for the difference in the extent to which they are moved by swinging of the arms 90a. Thus, it will be apparent that with this device there will be no danger of the containers being moved through the spacing device without contacting therewith.

After the containers are properly spaced on the conveyor, they are moved to the sealing head unit 4 which is adapted to seal the caps on the containers but to vacuumize and sterilize the head space and sterilize the cap before the sealing operation. This sealing head unit 4 is illustrated best in Figures 1 to 7, inclusive. The sealing head unit is supported above the conveyor belt by the plate 89. The plate 89 is supported on vertically disposed posts 105. I have shown three of these posts but any suitable number may be provided. These posts extend through the top of the table on opposite sides of the conveyor belt and are suitably mounted in the openings in the top of the table for vertical sliding movement relative thereto. The lower ends of these posts 105 are threaded as at 106. Cooperating with the threaded portion 106 of each of the posts is a sprocket 107 provided with a threaded opening through which the threaded portion of the post passes. Each of these sprockets is rotatably mounted but is supported on the table in such a manner that it will not move vertically by suitable means. It will be apparent that if the sprockets 107 are rotated the posts 105, which are connected to the plate 89 in such a manner that they will not rotate, will all be moved simul-

aneously either up or down. This will move the supporting plate 89 up or down. In order to rotate all the sprockets 107 simultaneously they are connected together by a sprocket chain 108. The chain 108 may be moved manually by means of a horizontally disposed rotatable shaft 109 which may be rotated by a handwheel 110 disposed outside of the housing 6. The shaft 109 is provided with a worm 111 meshing with a wormgear 112 freely rotatable on one of the posts 105. This wormgear 112 is connected by a sleeve 112a, which is freely rotatable on post 105, to one of the sprockets 107. Thus, by merely rotating the handwheel 110 the plate 89 may be raised or lowered.

It will be apparent that raising or lowering the plate 89 will cause the cap-feeding and applying unit 3 to be raised or lowered bodily. This will also cause the sealing head unit 4 to be raised or lowered bodily. Thus, by merely rotating the handwheel 110, the apparatus may be quickly adjusted to accommodate containers of different heights.

The sealing head unit 4 comprises a hollow guide member 113 of substantially rectangular cross section which is upwardly and rearwardly inclined relative to the plate 89 and which extends downwardly through the plate. The member 113 may be suitably secured to the plate and is disposed in alignment with the center line of the conveyor belt. This member 113 has reciprocably mounted therein a member 114 which may be termed a plunger. This member 114 carries the sealing head proper 115 on its lower end. The head proper 115 is removable and may be replaced with different sized heads. The plunger member 114 is adapted to be moved downwardly at regular intervals. For this purpose a cam member 116 is provided at the upper end of the plunger. This cam member 116 is keyed to a transversely extending shaft 117 which extends through upwardly projecting portions 118 of member 113 and is rotatably mounted in bearings disposed therein. The cam 116 is provided with a cam portion 119 which will engage a roller 120 on the upper end of the plunger 114 at regular intervals and force the plunger 114 and head 115 downwardly. A pair of tension springs 121 are provided which have their lower ends secured to the plunger 114 as at 122 and their upper ends secured to the guide member 113 as at 123. These springs 121 serve to draw the plunger 114 upwardly to its original position within member 113 after the cam portion 119 passes beyond the roller 120.

The shaft 117 that carries the cam 116 is driven by the same means that drives the conveyor and is rotated in timed relationship to the movement of the conveyor. Thus, the shaft 117 carries at one end a bevel gear 124 which is keyed thereto. This bevel gear 124 meshes with a bevel gear 125 keyed on a horizontal shaft 126 rotatably supported in bearings formed on the upper end of a support 127. This support 127 may be formed integral with the plate 89. The shaft 126 also has a bevel gear 128 keyed thereon. This bevel gear 128 meshes with a bevel gear 129 (Figure 4) which is keyed on the upper end of the vertically disposed shaft 30. Thus, the shaft 30 drives the shaft 117 and causes movement of the plunger 114. The shaft also drives the conveyor unit. The shaft 117 is provided with a sprocket 130 on its opposite end which drives the sprocket chain 86. Thus, the shaft 30 also drives the roller 74 disposed adjacent the lower

end of the cap chute. A balance flywheel 131 is also keyed on the end of shaft 117.

The sealing head proper is shown best in Figures 3, 4 and 6. It comprises an inverted channel-like structure which is open at both ends as at 132 and 133 so that the containers with the caps thereon may pass through the channel formation as they are carried along by the belt conveyor. The sealing head proper is closed 10 at its sides 134 and 135 and is provided with a steam channel 136 on its interior which extends over the top of the head and downwardly into each side thereof as indicated in Figure 6. A steam discharge port 137 is provided at the 15 center of the head proper and is directed downwardly. Steam discharge ports 138 are formed in each of the side walls 134 and 135 substantially midway between the ends of the channel-like structure. These steam discharge ports are 20 directed upwardly at an angle as indicated in Figure 6. The steam channel 136 in the head proper is in communication with a passageway 139 formed in the member 114. This passageway 139 is in communication with a transverse 25 passageway 140 having a steam inlet tube 141 threaded into its outer end. A flexible steam conduit 142 is connected to the tube 141. Member 113 is provided with slot 141' through which member 141 projects. The inner end of the passageway 140 is normally closed by a valve stem 143. This valve stem is slidably mounted in a bore formed in the member 114 and which is a continuation of the passageway 139. The stem 143 is provided with a plurality of longitudinally 30 spaced annular grooves 144 which serve as steam traps to prevent leakage. A compression spring 145 surrounds the upper end of the stem 143 and cooperates with an enlargement 146 thereon to normally move the stem from over the end of the passageway 140. However, the stem is moved downwardly against the force of this spring at regular intervals by means of a lever 147 bearing against the upper end thereof. This lever is pivoted as at 148 to the upper portion 40 of member 114. Intermediate its ends it is provided with a roller 149 engaged by a cam 150. The cam 150 is provided with a notched cam portion 151 which will be engaged by the roller 149 at regular intervals. The cam 150 is also keyed 45 on the shaft 117. The cam portion 151 of cam 150 is located circumferentially at about the same position as the cam portion 119 of cam 116. It is desirable for the steam valve to close at about the same time as the cam 116 operates to 50 force the plunger 114 downwardly.

It will be apparent that the sealing head is substantially parallel with the conveyor. When it is moved downwardly by the cam 116, it will follow a path which is inclined downwardly and forwardly so that when the sealing head is actually in contact with the cap on the jar, it is traveling with a downward and forward motion whose component is substantially the same as the rate of travel of the conveyor belt. When the sealing head is properly positioned relative to the articles on the conveyor and when one of the containers with the cap loosely thereon moves into the channel-like sealing head, the central steam jet 137 creates a partial vacuum which serves to lift the cap slightly from the jar and shown in Figure 6 so that the steam being delivered from jets 138 may more readily enter into the container as indicated in Figure 6. Apparently the jet 137 rarefies the air above the center of the cap. Moreover, flowing of the steam

out of the open ends 132 and 133 of the sealing head creates a zone of reduced pressure adjacent thereto which withdraws air from the head space at the upper end of the container which is immediately replaced by steam being delivered from the ports 138. I preferably employ low velocity steam jets to prevent entraining of air.

While steam is thus being introduced beneath the cap and into the container, the sealing head moves downward until it reaches its lowermost position and forces the cap down onto the container. At about the same instant the steam is cut off automatically by cam portion 151 forcing the valve stem 143 downwardly. The forcing of the rubber gasket over the upper end of the container produces a sealed closure which, of itself, serves to hold the cap on the container. Since the container is sealed substantially simultaneously with the injection of steam thereinto, the steam will not escape from the container before sealing. However, the condensation of the steam trapped in the head space in the container beneath the cap, which occurs immediately, produces a partial vacuum which is the main force serving to hold the cap on the jar and which also aids in preventing spoilage of the contents of the container. Immediately after the sealing action, the sealing head is automatically withdrawn upwardly and rearwardly. It will be apparent that the steam jet will also serve to sterilize the head space at the upper end of the container, the upper portion of the container and the cap applied thereto.

It will be noted from Figure 6, that when the steam jets lift the cap into contact with the sealing head, the skirt 40 of the cap still extends downwardly to a point below the upper edge of the container. As a result of this, even after the cap is lifted, the skirt of the cap will serve to confine the steam, injected into the container, during the continuous movement of the container and will, therefore, produce a more effective vacuum.

Due to manufacturing difficulties, the containers usually vary slightly in height. Therefore, it is desirable to provide some means in association with the sealing head unit to prevent injury to the upper ends of any containers which are of slightly greater height than the containers for which the sealing head unit is set to operate upon. For this purpose the roller 120 engaged by the cam 116 is carried by a cylindrical member 152 which is slidably mounted within the hollow upper portion of the plunger 114. A compression spring 153 is interposed between the inner end of the member 152 and the lower end of the socket in the member 114 in which it is disposed. The member 152 is provided at its inner end with a reduced centering portion 154 which extends into the spring 153. It will be apparent that if the sealing head proper 115 bears against the upper end of the container with too much force, the spring 153 will be compressed and, thereby, injury to the upper end of the container will be prevented. The sealing head unit can be so positioned that the sealing head will bear against the upper ends of all the containers with a resilient force.

From the preceding description the operation of the entire machine will be well understood. The conveyor will be continuously driven and the sealing head unit 4 and cap-feeding and applying unit 3 will be properly adjusted to accommodate the containers and caps to be used. The containers will be placed indiscriminately on the

conveyor which will first carry them between the fingers 42. The fingers 42 will center the containers on the conveyor so that they will be in alignment with the lower end of the cap chute. The containers will then be moved along and as they pass beneath the cap chute will withdraw caps therefrom as previously described. Then the articles will be moved into contact with the fingers 90 which will be moved apart at intervals to allow the containers to pass. This will cause the containers to be uniformly spaced along the conveyor belt. The containers with the caps loosely thereon will then be moved beneath the sealing head unit. The sealing head will be moved downwardly and also in the direction of movement of the conveyor at regular predetermined intervals so that the sealing head will contact with the caps of the successive containers. As previously explained the sealing head will vacuumize, sterilize and seal the caps on the containers.

In Figure 13, I show a slightly different form of cap-feeding means. In this form the member 56a which is similar to member 56 of Figure 11 is continued downwardly and is curved the same as the members 51 of the chute. The roller 74a in this instance is not positively driven and is mounted on member 77a similar to member 77 of Figure 11. This structure will operate substantially the same as that of Figure 11 with the exception that the container will withdraw the cap without the aid of the positively driven roller.

In Figures 14 and 15 I have illustrated a machine similar to that just described but which is provided with hydraulic means for operating the sealing head unit. In this instance the guide member 113a is substantially the same as the member 113 but is provided with a removable cap 113b. The plunger 114a is reciprocable in the member 113a and carries the sealing head proper 115 which is exactly the same as previously described. The plunger 114a is hollow and has a chamber 155 formed therein which is of cylindrical form. A piston 156 is disposed within this chamber. The plunger 114a can reciprocate relative to the piston 156 but packing 157 is provided for preventing leakage of hydraulic fluid in chamber 155 past the piston. The piston 156 is provided with a tubular extension 158 which is threaded into the cap 113b as at 159. This extension 158 has a central passageway 160 extending therethrough. It will be apparent that when fluid is forced through the passageway 160 into the chamber 155, the plunger 114a will be moved downwardly relative to the piston 156 performing the capping operation in the manner which will be apparent. For moving the plunger 114a upwardly a compression spring 121a is provided. This spring bears against a cap 114b provided at the upper end of member 114a and against the upper surface of the piston 156. When the plunger 114a is moved downwardly, this spring 121a will be compressed and as soon as the hydraulic pressure is released, the spring 121a will return the plunger 114a to its upper position.

A valve stem 143a is provided in the member 114a as before. This valve stem controls passage of steam through the passageway 140a which is substantially the same as the passageway 140. The other steam passageways in the member 114a and the head proper are the same as previously described with reference to the mechanically operated sealing head unit. The spring 145a at the

upper end of stem 143a normally tends to expand to move valve stem 143a to open position permitting steam to pass through passageway 140a. However, when the plunger 114a is in its uppermost position as illustrated in Figure 14, the upper end of the stem will bear against the cap 113b forcing the stem 143a into a position where passageway 140a is closed. However, as soon as plunger 114a moves downwardly the passageway 140a will be opened.

The extension 158 of piston 168 is connected by a conduit 161 to a unit 162 which will supply hydraulic fluid under pressure to the chamber 155 in the sealing head unit. This unit 162 is preferably enclosed in a housing 6a formed as a part of the table 1. This unit 162 embodies a fluid-tight housing having a chamber 163 which may be filled with hydraulic fluid through a plugged opening 164. Extending horizontally within the chamber 163 is a cylinder 165. This cylinder has a small inlet opening 166 through which fluid may pass from chamber 163 into the interior of the cylinder. The cylinder 165 is threaded into an extension 167 of the housing of unit 162 and to which the conduit 161 is connected. The cylinder 165 has a piston 168 movable therein. A compression spring 169 within the cylinder 165 tends to keep the piston 168 in the position indicated in Figure 14. In this position the plunger 114a and the capping head 115 will be in their uppermost positions. However, a cam lever 170 is provided for forcing the piston 168 to the right (Figure 14) at regular intervals. This lever 170 is keyed on a horizontal shaft 171 which extends through one of the side walls of the unit 162. The lower end of this lever bears against piston 168 as at 172. The shaft 171 may be rotated from a point outside the housing by an upstanding lever 173 which has a roller 174 that engages a cam 116a. The cam 116a may be driven from the electric motor in a manner similar to that by which the cam 116 is driven. The cam 116a is provided with cam portions 116b and 116c.

In the operation of this hydraulic device, when the cam 116a is rotated, the portion 116b will engage roller 174 swinging lever 170 about its pivot forcing piston 168 to the right. This closes the inlet opening 166 and forces fluid from the cylinder 165 through conduit 161 into chamber 155. The cam portion 116b causes the piston 168 to move sufficiently to cause sufficient downward movement of plunger 114a to permit movement of the valve stem 143a to open passageway 140a and allow steam to flow therethrough. The portion 116c of the cam then engages roller 174 causing lever 170 to move piston 168 a sufficient distance to force plunger 114a down to its lowermost position. The inlet opening 166 will serve as a means to supply hydraulic fluid from the chamber 163 to all the other portions of the system to compensate for leakage or contraction of the fluid in the system.

As previously described with reference to the mechanically operated capping head, the containers usually vary somewhat in height. Therefore, it is desirable to provide a safety means which will prevent too much pressure being applied by the capping head to the upper end of a container which is of a greater height than that for which the sealing head is adjusted. For this purpose, in the hydraulic system I provide a by-pass 175 leading directly from line 161 into chamber 163 above the point where the line 161 is connected

7 to cylinder 165. This by-pass is under the control of a relief valve 176 normally held in closed position by a spring 177. A setscrew 178 will vary the resistance of the spring. It will be apparent that the relief valve can be set to limit the pressure exerted by the capping head to a maximum. When this pressure is exceeded, the relief valve will open allowing the fluid to flow directly from line 161 into the chamber 163.

10 It will be apparent from the above description that I have provided a greatly simplified apparatus for applying and sealing closures on containers. The caps are first positioned on the containers loosely, are then lifted and the upper portion of the containers vacuumized and sterilized and simultaneously the caps are sterilized, and then the caps are forced into sealing engagement with the container. The containers will be vacuumized and sealed quickly and effectively. The machine is very simple and can be built at a comparatively low cost. It may be readily adjusted to operate upon containers of various sizes. Furthermore, means is provided on the machine for preventing injury to the containers even though they vary in height.

15 Many other advantages will be apparent from the preceding description, the drawings and the following claims.

20 Having thus described my invention, what I claim is:

25 1. Apparatus of the type described comprising a conveyor for supporting containers, means for continuously moving the conveyor, means associated with the conveyor for centering the containers transversely of the conveyor, a cap-30 applying means disposed in superimposed relationship to the conveyor substantially midway between the side edges thereof for positioning caps loosely on the containers as they are moved therebeneath, means associated with the conveyor for uniformly spacing the containers previously disposed on the conveyor as they are moved along, and a sealing head unit disposed in superimposed relationship to said conveyor, said sealing head unit embodying a sealing head proper having steam jets associated therewith which will lift the caps from the containers and will simultaneously inject steam into the upper ends of the containers, and means for moving the sealing head downwardly to force the caps into position on the containers during movement of the containers by the conveyor.

35 2. Apparatus of the type described comprising a conveyor for supporting containers which

50 55 loosely rest thereon, means for continuously moving the conveyor, means associated with the conveyor for centering the containers transversely of the conveyor, a cap-feeding and applying means disposed in superimposed relationship to the conveyor substantially midway between the side edges thereof for positioning the caps loosely on the containers as they are moved therebeneath, said means embodying a device for feeding

60 65 the caps into a position where they will be engaged by the containers as they move therebeneath, means for uniformly spacing the containers on the conveyor as they are moved along, and a sealing head unit disposed in superimposed relationship to said conveyor, said sealing head

70 75 unit embodying a sealing head proper having steam jets associated therewith which will lift the caps from the containers and will simultaneously inject steam into the upper ends of the containers, and means for moving the sealing

head downwardly at regular intervals to force the caps into position on the containers during movement of the containers by the conveyor, and means for supplying steam to the steam jet at regular intervals so timed relative to the movement of the sealing head that the steam will be injected into the containers before the caps are sealed thereon.

3. Apparatus of the type described comprising a conveyor for supporting containers, means for continuously moving the conveyor, means associated with the conveyor for centering the containers transversely of the conveyor, a cap-applying means disposed in superimposed relationship to the conveyor substantially midway between the side edges thereof for positioning the caps loosely on the containers as they are moved therebeneath, means associated with the conveyor for uniformly spacing the containers previously disposed on the conveyor as they are moved along, and a sealing head unit disposed in superimposed relationship to said conveyor, said sealing head unit embodying a sealing head proper, and means for moving said sealing head downwardly at an angle to the path of movement of the conveyor so that the sealing head will have a component of motion corresponding to that of the conveyor and will force the caps into position on the containers during movement of the containers by the conveyor.

4. In apparatus of the type described, a conveyor for supporting containers, means for continuously moving the conveyor, and a sealing head unit disposed in superimposed relationship to said conveyor and adapted to force caps previously applied to the containers into sealing engagement therewith, said sealing head unit embodying a sealing head adapted to engage the caps, and means for reciprocating said sealing head in a path at an angle to the path of movement of the conveyor, said means serving to move the head downwardly at intervals so that the sealing head will have a component of motion corresponding to that of the conveyor and will force the caps into position on the containers during movement of the containers by the conveyor.

5. Apparatus of the type described comprising a conveyor for supporting containers, means for moving the conveyor, a sealing head unit associated with the conveyor for forcing caps previously applied to containers into sealing engagement therewith, said sealing head unit embodying a sealing head of channel shape to permit movement of the upper ends of the containers therethrough, said sealing head having steam jets associated therewith, and means for moving the sealing head relative to the containers in such a manner that it will force the caps into sealing engagement with the containers.

6. In apparatus of the type described, a conveyor for supporting containers, means for continuously moving the conveyor, a sealing head unit disposed in superimposed relationship to said conveyor and adapted to force the caps previously applied to the containers into sealing engagement therewith, said sealing head unit embodying a sealing head adapted to engage the caps, means for reciprocating said sealing head in a path at an angle to the path of movement of the conveyor, said means serving to move the head downwardly at intervals so that the sealing head will have a component of motion corresponding to that of the conveyor and will force the caps into position on the containers during movement of the containers by the conveyor, and means as-

sociated with said sealing head unit to prevent the sealing head from exerting a force on the upper ends of the containers in excess of a pre-selected maximum.

5. 7. In apparatus of the type described, a conveyor for supporting containers, means for continuously moving the conveyor, a sealing head unit disposed in superimposed relationship to said conveyor and adapted to force the caps previously applied to the containers into sealing engagement therewith, said sealing head unit embodying a sealing head adapted to engage the caps, means for reciprocating said sealing head in a path at an angle to the path of movement of the conveyor, said means serving to move the head downwardly at intervals so that the sealing head will have a component of motion corresponding to that of the conveyor and will force the caps into position on the containers during movement of the containers by the conveyor, said last-named means including a hydraulic system.

8. In apparatus of the type described, a conveyor for supporting containers, means for continuously moving the conveyor, a sealing head unit disposed in superimposed relationship to said conveyor and adapted to force the caps previously applied to the containers into sealing engagement therewith, said sealing head unit embodying a sealing head adapted to engage the caps, means for reciprocating said sealing head in a path at an angle to the path of movement of the conveyor, said means serving to move the head downwardly at intervals so that the sealing head will have a component of motion corresponding to that of the conveyor and will force the caps into position on the containers during movement of the containers by the conveyor, said last-named means including a hydraulic system, and means associated with said hydraulic system for preventing the sealing head from exerting a force in excess of a preselected maximum on the upper ends of the containers.

9. Apparatus of the type described comprising a conveyor for supporting containers, means for continuously moving the conveyor, a cap-applying unit disposed in association with the conveyor for positioning caps loosely on the containers as they are moved past said unit, means associated with the conveyor for uniformly spacing the containers previously disposed on the conveyor as they are moved along, and a sealing head unit disposed in superimposed relationship to said conveyor, said sealing head unit embodying a sealing head proper having means associated therewith for lifting the caps from the containers and for simultaneously injecting steam into the upper ends of the containers, means for moving the sealing head downwardly to force the caps into position on the containers during movement of the containers by the conveyor, and control means for actuating said steam injecting means and said sealing head moving means substantially simultaneously.

10. Apparatus of the type described comprising a conveyor for supporting containers, means for continuously moving the conveyor, a cap-applying unit disposed in association with the conveyor for positioning caps loosely on the containers as they are moved past said unit, and a sealing head unit disposed in superimposed relationship to said conveyor, said sealing head unit embodying a sealing head proper having means associated therewith for lifting the caps from the containers and for simultaneously injecting steam into the upper ends of the containers, means for moving

the sealing head downwardly to force the caps into position on the containers during movement of the containers by the conveyor, and control means for actuating said steam injecting means and said sealing head moving means substantially simultaneously.

11. Apparatus of the type described comprising a conveyor for supporting containers having caps loosely applied thereto, means associated with the conveyor for uniformly spacing the containers previously disposed thereon as they are moved along, and a sealing head unit embodying a sealing head proper having means associated therewith for lifting the caps from the containers and simultaneously injecting steam into the upper end of the containers, means for moving the sealing head downwardly to force the caps into position on the containers during movement of the containers by the conveyor, and control means for actuating said steam injecting means and said sealing head moving means substantially simultaneously.

12. Apparatus of the type described comprising a conveyor for supporting containers having caps loosely applied thereto, and a sealing head unit embodying a sealing head proper having means associated therewith for lifting the caps from the containers and simultaneously injecting steam into the upper end of the containers, means for moving the sealing head downwardly to force the caps into position on the containers during movement of the containers by the conveyor, and control means for actuating said steam injecting means and said sealing head moving means substantially simultaneously.

13. In apparatus for sealing containers having caps loosely applied thereto, a sealing head, said sealing head embodying a flat plate disposed above the cap, said plate being provided with a jet opening disposed centrally relative to the cap through which steam is forced and which will serve to lift the cap from the container, said sealing head being also provided with upwardly directed steam jet openings adapted to supply steam between the cap and the upper end of the container.

14. Apparatus of the type described comprising a conveyor for supporting containers, means for continuously moving the conveyor, a sealing head unit associated with the conveyor for forcing caps previously applied to containers into sealing engagement therewith, said sealing head unit embodying a sealing head of channel shape to permit movement of the upper ends of the containers therethrough, said sealing head having steam jets associated therewith, and means for moving the sealing head relative to the containers in such a manner that it will force the caps into sealing engagement with the containers during their movement with the conveyor.

15. Apparatus of the type described comprising a conveyor for supporting containers, a cap feeding and applying means disposed in superimposed relationship to the conveyor for positioning caps loosely on the containers as they are moved there-

beneath, means for uniformly spacing the containers on the conveyor, a sealing head unit disposed in superimposed relationship to said conveyor, said sealing head unit embodying a sealing head proper having steam jets associated therewith which will lift the caps from the containers and will simultaneously inject steam into the upper ends of the containers, means for moving the sealing head downwardly at regular intervals to force the caps into position on the containers during movement of the containers by the conveyor, and means for supplying steam to the steam jets at regular intervals so timed relative to the movement of the sealing head that the steam will be injected into the containers before the caps are sealed thereon.

16. Apparatus of the type described comprising a conveyor for supporting containers, having caps loosely applied thereto, in uniformly spaced relationship, a sealing head unit disposed in superimposed relationship to said conveyor, said sealing head unit embodying a sealing head proper having steam jets associated therewith which will lift the caps from the containers and will simultaneously inject steam into the upper ends of the containers, means for moving the sealing head downwardly at regular intervals to force the caps into position on the containers during movement of the containers by the conveyor, and means for supplying steam to the steam jets at regular intervals so timed relative to the movement of the sealing head that the steam will be injected into the containers before the caps are sealed thereon.

17. Apparatus of the type described comprising a conveyor for loosely supporting containers, means for continuously moving the conveyor, means associated with the conveyor for uniformly spacing the containers previously disposed on the conveyor as they are moved along, said means including members adapted to be projected over the conveyor at regular intervals to interrupt movement of the containers with the conveyor, a sealing head unit disposed in superimposed relationship to said conveyor, said sealing head unit embodying a sealing head proper, and means for reciprocating said sealing head in a path at an angle to the path of movement of the conveyor, said means serving to move the head downwardly at intervals so that the sealing head will have a component of motion corresponding to that of the conveyor and will force the caps into position on the containers during movement of the containers by the conveyor.

18. In apparatus for sealing containers having caps loosely applied thereto, a sealing head, said sealing head embodying a flat plate disposed above the cap, said plate being provided with a jet opening disposed centrally relative to the cap through which steam is forced and which will serve to lift the cap from the container, said sealing head being provided with additional steam jet openings adapted to direct steam between the cap and the upper end of the container.

WILLIAM D. BELL.
